(57) **CLAIM**

(21) Appl. No.: **29/328,181**

The ornamental design for a baseboard molding trim, as shown in the accompanying drawings.

(22) Filed: **Nov. 20, 2008**

DESCRIPTION

Related U.S. Application Data

(62) Division of application No. 29/275,277, filed on Dec. 20, 2006, now Pat. No. Des. 583,488.

FIG. 1 is a perspective view of the baseboard molding trim for use on an outside corner;

(51) **LOC (9) Cl.** **25-01**

FIG. 2 is a front elevation view thereof, viewed toward one of the vertical walls;

(52) **U.S. Cl.** **D25/136**

FIG. 3 is a rear elevation view thereof, viewed toward one of the vertical walls;

(58) **Field of Classification Search** **D25/136,**

FIG. 4 is a front elevation view, viewed toward the opposite vertical walls;

D25/102, 55, 58, 121, 199; D8/402–403,

FIG. 5 is a rear elevation view, viewed toward the opposite vertical walls;

D8/499, 400; 52/287.1, 272.273, 275; D6/491,

FIG. 6 is a top plan view of FIG. 1; and,

D6/492, 495

FIG. 7 is a bottom plan view of FIG. 1.

See application file for complete search history.
